US00D849761S

(12) United States Design Patent (10) Patent No.: US D849,761 S
(45) Date of Patent: * May 28, 2019

(54) DISPLAY SCREEN OR PORTION THEREOF WITH GRAPHICAL USER INTERFACE

(71) Applicant: STATE FARM MUTUAL AUTOMOBILE INSURANCE COMPANY, Bloomington, IL (US)

(72) Inventors: Ben Schoer, Tucker, GA (US); Neil Stoeckle, San Francisco, CA (US)

(73) Assignee: STATE FARM MUTUAL AUTOMOBILE INSURANCE COMPANY, Bloomington, IL (US)

() Term: 15 Years

(21) Appl. No.: 29/630,634

(22) Filed: Dec. 21, 2017

(51) LOC (11) Cl. 14-04

(52) U.S. Cl.

USPC D14/485

(58) Field of Classification Search

USPC D14/485-495

CPC G06F 3/048-3/04897

See application file for complete search history.

(57) CLAIM

The ornamental design for a display screen or portion thereof with graphical user interface, as shown and described.

DESCRIPTION

The sole FIGURE shows a display screen or portion thereof with graphical user interface showing our new design. The peripheral dashed broken lines illustrate a display screen or portion thereof and form no part of the claimed design.

1 Claim, 1 Drawing Sheet
